C. H. CONGDON,

PITCH PIPE.

APPLICATION FILED APR. 3, 1920.

1,437,747.

Patented Dec. 5, 1922.

CHARLES H. CONGDON, Inventor

By HIS Attorney O.V. Thiele

UNITED STATES PATENT OFFICE.

CHARLES H. CONGDON, OF EAST STROUDSBURG, PENNSYLVANIA.

PITCH PIPE.

Application filed April 3, 1920. Serial No. 371,088.

To all whom it may concern:

Be it known that I, CHARLES H. CONGDON, a citizen of the United States, and resident of East Stroudsburg, in the county of Monroe and State of Pennsylvania, have invented certain new and useful Improvements in Pitch Pipes, of which the following is a specification.

My invention relates to pitch pipes and has for its object the production of a device of this class which shall be inexpensive to make, which shall have the twelve notes comprised in a chromatic scale so arranged relatively that the notes of the chords most commonly used shall be placed in such order that they can be conveniently played in succession; in which inhalations and exhalations may as far as possible alternate in sounding in sequence the notes of the more commonly used chords; and in which certain mechanical advantages shall be found, which are pointed out in greater detail in the following description.

The invention will be readily understood from the following description, which is to be ready in connection with the accompanying drawing. In the latter, Figs. 1, 2, and 3 are respectively top, front and end views of my device, some portions being sectioned in Fig. 2; Fig. 4 is a central, longitudinal, sectional view of the device, some parts being omitted; Fig. 5 is a top view of Fig. 4; Figs. 6 and 7 are sectional views of Fig. 4 on lines 6—6 and 7—7 respectively, looking in the direction indicated by the arrows; Fig. 8 is a top view of the lower reed plate; Fig. 9 is a sectional view on line 9—9 of Fig. 4; Figs. 10 11, and 12 are views similar to Figs. 4, 2, and 3 respectively of a modification; while Fig. 13 is a detail of this modification shown on an enlarged scale.

The base 1 can be made of any material desired, but is preferably made of some substance such as hard rubber which can be molded and thereafter hardens and becomes impervious to moisture and which is not readily subject to deterioration. It is seen to be generally of the shape of a rectangular block. The two flat faces of the block are provided with certain chambers, all of a depth a little less than half its thickness. The chambers on the under side are thus separated from those on the upper by a central wall or partition 2. There are seven such chambers on each side of the block,

and those of one side lie directly opposite those of the other. The chambers of what is the upper side in Figs. 2 and 4 are given the reference numerals 3, 4, 5, 6, 7, 8, and 9, while those on the lower side lying directly below them are numbered respectively 3^a, 4^a, 5^a, 6^a, 7^a, 8^a, and 9^a. The central chambers 6 and 6^a are closed on their four sides; the chambers 3, 3^a, 9, and 9^a open to the end by means of the channels 10, 10^a, 11, and 11^a respectively; the chambers 4, 4^a, 7, and 7^a open toward one edge of the base; while the chambers 5, 5^a, 8, and 8^a open toward the other edge. 12 and 13 are holes through the base whose purpose will appear later. The ends of the base 1 are seen to be rounded to the arc of a circle.

Secured by means to be presently described to the bottom and top of the base 1 are the two reed plates 14 and 15. They conform in outline to the base, so that when they are assembled with it their edges are alined with its edges.

The reed plates bear six reeds each, designated in the drawing by the conventional characters of the musical notes they sound, those of the upper plate being, from left to right, B_b, F_#, C_#, C, G and A; and those of the lower plate E_b, A_b, E, F, B, and D. It will be noted that the reeds are in both cases on the upper side of the reed plate.

The reed plates are pierced by holes 13^a in the same relative positions as the holes 13 in base 1.

The two cover plates 16 and 18 (see Figs. 1 and 2) are provided with holes 17, through which air may enter or leave; and at the ends are formed the depressions 19^a bringing the metal at these points into the same plane with the edge of the cover plates. The holes 19 register with the holes 13 and 13^a of the base and the reed plates. A circular depression 20 is made in the center of each cover plate 16 and 18, its bottom being on a level with the depressions 19^a.

In Fig. 4 will be noted the fact that the two reed plates are slightly sprung or curved. They are shown in this figure as they appear when placed in their positions relative to the base 1 but not yet secured to it. Both have their convex side toward the base 1.

In Fig. 2 the parts are shown assembled and it will be noted that the reed plates are brought into contact with the base 1 at their

ends by means of the rivets 21, which pass through the alined openings 19, 13^a, and 13. Contact at all points between the ends of the reed plates with the base 1 is assured 5 by the curvature given to the reed plates.

Each of the reeds is seen to lie above or below one of the chambers 3 to 9 or 3^a to 9^a.

The bottom of each depression 20 bears on the corresponding reed plate.

10 At points adjacent to the openings leading to the chambers 3, 4, etc., and 3^a, 4^a, etc., there are marked on the cover plates the characters denoting the notes given by the corresponding reeds. See Figs. 1 and 2.

15 From a perusal of the above description it will be apparent that the parts making up this pitch pipe are very readily assembled and secured together.

In use the pitch pipe is held by the thumb 20 and forefinger of one hand, their tips engaging the depressions 19 and 20 of the cover plates 16 and 18. This permits the person using the instrument to twirl it so as to bring the required openings into convenient 25 position for sounding the notes. The arrangement described makes it possible to use the entire periphery of the pipe for openings and thus to reduce the entire instrument to a very convenient length.

30 The covers cannot be crushed by the pressure exerted by the thumb and forefinger, as the bottoms of the depressions 19 and 20 bear against the reed plates.

As an illustration of the natural and easy 35 sequence in which the notes of a usual chord occur, the F chord may be selected. The notes composing it—F, C, A—are found, referring to their positions as illustrated in the drawings, at the right of the upper edge 40 and at the right end; and to sound them in their proper sequence the operator will first exhale into the upper right opening, then inhale from the right end opening, and then inhale from the upper right opening. Thus 45 it is seen how well these are placed, and how easily the transition from each to the next is effected. By trying other chords it will be found that for those more commonly used the arrangement of the reeds and the 50 sequence of inhalations and exhalations are very convenient.

In the variation illustrated in Figs. 10 to 13 the reed plates are sprung in the opposite direction, so that their concave sides 55 face the base plate. The parts are secured together by a single device extending through the central openings 25, 25^a, and 26 in the reed plates and the base plate and through corresponding holes in the cover 60 plates at the bottoms of the depressions 19 and 20. See Fig. 13 for an enlarged view of this feature. Instead of a rivet being employed, the parts are secured together by means of the screw 27 which engages the 65 special nut 28. Both of these parts have

bevelled heads engaging the cover plates and are provided with slots so they may be turned relatively to each other by means of a screw driver. The advantage of securing the parts together in this detachable 70 manner is that the pipe may be taken apart for cleaning and repairs.

To prevent the parts from rotating relatively to each other about screw 27 the reed plates 14^a and 15^a are slightly offset or indented as at 29, the offset portions extending a slight distance into the channels 10, 10^a, 11, and 11^a. Similar offsets or indentations are made in the cover plates to extend into those of the reed plates as will be clearly seen by an inspection of Fig. 12.

It will be found advisable in practice to spring the cover plates also by a slight amount, thus ensuring their becoming properly seated.

When my invention is put into practice by others there will no doubt be made some variations from the precise forms hereinabove described, without a departure from the spirit of the appended claims. Thus in 90 the form first described screws similar to those of the second form or of some other preferred form may be used in place of the rivets; or if desired the second form may use a rivet or eyelet in place of the 95 screw. It will in other words be understood that the description is by way of illustration only and not by way of restriction to the precise details.

What I claim is:—

1. In a device of the class described, the combination of a base with a plane face, a reed plate juxtaposed to it and sprung relatively to it, that side tending to be concave being toward the base, and means engaging the reed plate substantially at its center securing the two together.

2. In a device of the class described, the combination of a base having two parallel plane faces, two reed plates juxtaposed respectively to these two faces, each of the reed plates being sprung relatively to the base so that it tends to assume an arched shape concave toward the base, and readily detachable means engaging the reed plates substantially at their centers and holding the plates in engagement with the base throughout their lengths.

3. In a device of the class described, the combination of a base having two parallel plane faces, two reed plates juxtaposed respectively to these two faces, each of the reed plates being sprung relatively to the face so that it tends to assume an arched shape concave toward the base, and readily detachable 125 means engaging the reed plates substantially at their centers and holding the plates in engagement with the base throughout their lengths, the base being provided with channels in its surface, and the plates each hav- 130

- ing an offset portion engaging a channel to keep them from turning relatively to the base.
4. In a device of the class described, the combination of a base having two parallel plane faces, two reed plates juxtaposed respectively to these faces, each of the reed plates being sprung relatively to the base so that it tends to assume an arched shape 10 curve toward the base, two cover plates engaging the reed plates on the sides away from the base, each cover plate being provided with a circular depression at its center whose bottom contacts with the reed plate, and 15 means passing through aligned openings in the said depressions of the cover plates, in the reed plates and in the base securing them all together, and means on the reed plates and covers to keep them from turning relatively 20 to the base or to each other.
5. In a device of the class described the combination of a base having a plane face, a reed plate in contact with this face, a cover plate in contact with the free face of the 25 reed plate along a line adjacent to its outer edge and raised from it at other points, said cover plate having an offset portion at its center contacting with the reed plate.
6. A device of the class described comprising in combination a base having two 30 parallel plane faces, two reed plates in contact respectively with these two faces, two
- cover plates in contact respectively with the two free faces of the reed plates along a line adjacent to their outer edges, and raised from 35 them at other points, said cover plates each having an offset portion at its center contacting with the reed plate.
7. A device of the class described comprising in combination a base, two reed plates, and two cover plates, each of the cover plates having a central circular depression, whereby the device may be held with the thumb and a finger engaging the two depressions and readily turned into any desired position.
8. In a device of the class described the combination of a base with two flat parallel faces each having six chambers, those of one face lying opposite those of the other, the 40 four end chambers having channels leading out to the ends of the base, the other chambers of both sides opening alternately to the two edges of the base, and two reed plates secured to the parallel faces of the base, each bearing six reeds corresponding to the six 45 chambers on that side of the base, the twelve reeds being tuned to sound the twelve notes of a chromatic scale.

Signed at New York in the county of New 60 York and State of New York this 19th day of March A. D., 1920.

CHARLES H. CONGDON.
